UNITED STATES PATENT OFFICE.

HOWARD A. THOMPSON, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed February 17, 1926. Serial No. 88,849.

My invention relates to railway traffic controlling apparatus, and particularly to apparatus of the type comprising a plurality of sections of railway track separated by insulated joints and each provided with governing means controlled by currents separately supplied to the several sections.

One object of my present invention is to prevent improper operation of the governing means for one such section by current from an adjacent section.

I will describe one form of railway traffic controlling apparatus embodying my invention, and will then point out the novel features thereof in claims.

The accompanying drawing is a diagrammatic view illustrating one form of railway traffic controlling apparatus embodying my invention.

Referring to the drawing, the reference characters 1 and 1^a designate the track rails of a stretch of railway track over which traffic normally moves in the direction indicated by the arrow. These track rails are divided into a plurality of successive track sections A—B, B—C, etc., by means of insulated joints designated by the reference characters 2 and 3, with exponents corresponding to the locations and inserted in the track rails 1 and 1^a, respectively. Each track section is provided with a track transformer designated by the reference character T with an appropriate exponent and having a secondary 6 constantly connected across the rails adjacent the exit end of the associated section. An impedance 4 is interposed between rail 1 and one terminal of each secondary 6. A similar impedance 5 is interposed between rail 1^a and the other terminal of each secondary 6. The primary 7 of each track transformer T is constantly supplied with alternating current from secondary 8 of an associated line transformer designated by the reference character L with an exponent corresponding to the location. The primary 9 of each line transformer is constantly supplied with alternating current from a suitable source such as an alternator W over line wires 40 and 40^a. Each track section is further provided with a track relay designated by the reference character R with an appropriate distinguishing exponent and comprising two windings 10 and 11. Winding 10 of each

track relay is constantly connected across the rails adjacent the entrance end of the corresponding section.

An asymmetrical unit, designated by the reference character 12 with an exponent corresponding to the location, is connected across each insulated joint 2 in rail 1. A similar asymmetrical unit, designated by the reference character 13 with an appropriate exponent, is connected across each insulated joint 3 in rail 1^a. The asymmetrical units 12 and 13 may be of any suitable form such for example as the rectifiers illustrated in an application for Letters Patent of the United States, Serial No. 1111, filed January 7, 1925, by Lars O. Grondahl, for uni-directional current carrying devices.

Associated with each track relay are two detector relays designated by the reference characters G and H, respectively, with exponents corresponding to the location. Each of these detector relays is designed to be operated by uni-directional current and if supplied with alternating current requires an electromotive force across its terminals of many times the electromotive force required to operate the relay on uni-directional current. In apparatus embodying my invention the detector relays are never supplied with alternating current of sufficient electromotive force to operate the relays, and for purposes of the present disclosure it is therefore correct to state that the detector relays are responsive to uni-directional current but not to alternating current.

Referring particularly to the apparatus located at point B, detector relay G^B is provided with a circuit which may be traced from secondary 6 of track transformer T^B, through wires 14 and 15, winding of relay G^B, wire 16, rail 1 of section B—C, wire 17, asymmetrical unit 12^B, wire 18, rail 1 of section A—B, wire 19, impedance 4 and wires 20 and 20^a back to secondary 6. Under normal conditions therefore, the alternating current supplied by secondary 6 of transformer T^B is changed by the asymmetrical unit 12^B to uni-directional current which energizes relay G^B. In similar manner, relay H^B is provided with a circuit which may be traced from secondary 6 of transformer T^B, through wires 20^a and 21, winding of relay H^B, wire 22, rail 1^a of section B—C, wire 23, asymmetrical unit

13^B, wire 24, rail 1^a of section A—B, wire 25, impedance 5, and wire 14, back to secondary 6. The current from secondary 6 is rectified by asymmetrical unit 13^B and the 5 uni-directional current which therefore flows through relay H^B energizes this relay.

The detector relays G and H control the supply of current to winding 11 of the associated track relay R, the circuit for this 10 winding being complete only when the detector relays are both energized. Referring particularly to relay R^B, when relays G^B and H^B are both energized current flows from secondary 8 of line transformer L^B, through 15 wires 26, 27 and 28, front contact 29 of relay H^B, wire 30, front contact 31 of relay G^B, wire 32, winding 11 of relay R^B, and wires 33, 34 and 35, back to secondary 8 of transformer L^B. When windings 10 and 11 20 are both supplied with alternating current, this relay becomes energized and closes its front contact.

The trackway circuits thus far described 25 may be utilized to control governing means of any suitable form. In the apparatus here shown each track section is provided with a trackway signal designated by the reference character S with an exponent corresponding to the location and capable of indicating "proceed" or "stop". When relay R^B is energized, current flows from secondary 8 of line transformer L^B, through wires 26, 27 and 36, front contact 37 of relay R^B, wire 28, operating mechanism of signal S^B, and wires 39, 34 and 35, back to secondary 8 of transformer L^B. When this circuit is 30 closed, signal S^B indicates "proceed". When relay R^B is deenergized, the operating circuit for signal S^B is broken and the signal 35 then indicates "stop".

As shown in the drawing, section A—B and the section to the right of point C are unoccupied, but a train, indicated diagrammatically at V, occupies section B—C. All 40 detector relays G and H are energized and current is therefore supplied to winding 11 of each track relay R. Current is also supplied to winding 10 of relays R^C and R^A, so that these relays are energized and signals S^C and S^A indicate "proceed". Winding 10 45 of relay R^B is shunted by the wheels and axles of train V so that relay R^B is de-energized and signal S^B indicates stop.

Under some conditions of operation a 50 dangerous condition might exist should one or both of the insulated joints 2, 3 break down at the entrance to an occupied section thereby permitting current from the adjacent section to energize the track relay for such occupied section. For example, I will 55 assume that insulated joint 2^B breaks down. Current might then flow from secondary 6 of transformer T^B, through wires 20^a and 20, impedance 4, wire 19, through rail 1 60 past insulated joint 2^B to winding 10 of

relay R^B, then from rail 1^a of section B—C to rail 1^a of section A—B through the ground around insulated joint 3^B, and so through 25, 5 and 14 to secondary 6. The 65 resistance between rail 1^a of section B—C and rail 1^a of section A—B through the ground might, under certain conditions, be 70 so low that the current supplied to winding 10 under these conditions would be of sufficient magnitude to cause operation of relay R, if current were at the same time being supplied to winding 11 of this relay. In 75 similar manner should insulated joint 3^B break down, current might flow from secondary 6 of transformer T^B, through wire 14, impedance 5, wire 25 and rail 1^a past insulated joint 3^B to winding 10 of relay R, and from rail 1 of section B—C to rail 1 of section A—B through the ground back to the other terminal of secondary 6. 80 Should insulated joints 2^B and 3^B both break down the dangerous condition would simply be exaggerated because secondary 6 of transformer T^B would then be connected directly with winding 10 of relay R^B. In 85 either of these cases therefore it will be manifest that should an insulated joint break down and cause improper operation of relay R, signal S^B would indicate proceed even though section B—C were occupied by 90 a train. With apparatus embodying my invention this condition can not arise. For example, if insulated joint 2^B breaks down, the asymmetrical unit 13^B is shunted so that 95 detector relay G^B is supplied with alternating current instead of uni-directional current from transformer T^B. But the magnitude of the alternating electromotive force then applied to relay G^B is not sufficient 100 to operate the relay which therefore becomes de-energized, opening its front contact 31 and discontinuing the supply of alternating current to winding 11 of relay R^B. The track relay R^B is therefore deenergized, even though current may be supplied from 105 transformer T^B to winding 10 of this relay because of the broken down insulated joint 2^B. In similar manner, if insulated joint 3^B breaks down, asymmetrical unit 13^B is 110 shunted so that alternating current is supplied to relay H^B and this relay thereupon becomes de-energized. The opening of front contact 29 of relay H^B de-energizes 115 winding 11 of a track relay R^B so that the track relay is open, even though current 120 might be supplied to winding 10 thereof from transformer T^B. It follows from the foregoing that if either of the insulated joints break down, the associated detector relay becomes de-energized, thereby preventing the supply of alternating current to winding 11 of the adjacent track relay R. It is therefore impossible for a track relay 125 to be improperly operated by current supplied thereto from the track transformer 130

for an adjacent section because of broken down insulated joints.

It should be noted that the integrity of the circuits for the detector relays are completely checked. If, for example, the circuit for relay G^B becomes open at any point the relay will open, thereby opening the circuit for winding 11 of relay R^B and preventing a dangerous condition. On the other hand, if either of the rectifiers becomes short circuited, the corresponding detector relay will be supplied with alternating current and will open its front contact, thereby discontinuing the supply of alternating current to the adjacent track relay and preventing improper operation of the relay.

It should be noted further that by including the impedances 4 and 5 in the circuits for the detector relays assurance is given that these relays will be energized even when a train is located directly at the points of connection of the track transformer, a sufficient electromotive force being supplied to each detector relay by the potential drop across one of the impedances 4 or 5. Under normal conditions therefore the detector relays G and H are always energized and become de-energized only when some fault occurs against which protection is desirable.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination, two adjacent sections of railway track separated by an insulated rail joint, a source of alternating current connected with the rails of one such section, a track relay having a first winding connected with the rails of the other section and a second winding, an asymmetrical unit connected in parallel with said insulated joint, a detector relay responsive to uni-directional current but not to alternating current, a circuit for said detector relay including a source of alternating current and said asymmetrical unit, and means controlled by said detector relay for supplying alternating current to the second winding of said track relay.

2. In combination, two adjacent sections of railway track separated by an insulated rail joint, a source of alternating current connected with the rails of one such section, a track relay having a first winding connected with the rails of the other section and a second winding, a detector relay, means for normally energizing said detector relay and for de-energizing the detector relay if said joint breaks down, and means con-

trolled by said detector relay for supplying alternating current to the second winding of said track relay.

3. In combination, two adjacent sections of railway track separated by insulated joints in the track rails, a source of alternating current connected with the rails of one such section, a track relay having a first winding connected with the rails of the other section and a second winding, two detector relays, means for normally energizing one said detector relay such relay becoming de-energized if one of said joints breaks down, means for normally energizing said second detector relay such second detector relay becoming de-energized if the other said joint breaks down, and means controlled by said two detector relays for supplying alternating current to the second winding of said track relay.

4. In combination, two adjacent sections of railway track separated by insulated joints in the track rails, a source of alternating current connected with the rails of one such section, a track relay having a first winding connected with the rails of the other section and a second winding, an asymmetrical unit connected in parallel with one said insulated joint, a detector relay responsive to uni-directional current but not to alternating current, means for connecting said detector relay with said source through said asymmetrical unit so that the relay is normally supplied with uni-directional current but is supplied with alternating current if said one insulated joint breaks down, and means controlled by said detector relay for supplying alternating current to the second winding of said track relay.

5. In combination, two adjacent sections of railway track separated by insulated joints in the track rails, a source of alternating current connected with the rails of one such section, a track relay having a first winding connected with the rails of the other section and a second winding, an asymmetrical unit connected in parallel with one said insulated joint, a detector relay responsive to uni-directional current but not to alternating current, means for connecting said detector relay with said source through said asymmetrical unit so that the relay is normally supplied with uni-directional current but is supplied with alternating current if said one insulated joint breaks down, and means for supplying alternating current to the second winding of said track relay only when said detector relay is energized.

6. In combination, two adjacent sections of railway track separated by insulated joints in the track rails, a source of alternating current connected across the rails of one section, a track relay having one winding connected across the rails of the other sec-

tion and a second winding, two asymmetrical units one connected across each of said insulated joints, two detector relays each responsive to uni-directional current but not to 5 alternating current, a circuit for one said detector relay including a source of alternating current and one of said asymmetrical units, a circuit for the other detector relay including a source of alternating current 10 and the remaining asymmetrical unit, and means controlled by said two detector relays for supplying alternating current to the second winding of said track relay.

7. In combination, two adjacent sections 15 of railway track separated by insulated joints in the track rails, a source of alternating current connected across the rails of one section, a track relay having one winding connected across the rails of the 20 other section and a second winding, two asymmetrical units one connected across each of said insulated joints, two detector relays each responsive to uni-directional current but not to alternating current, a circuit 25 for one said detector relay including a source of alternating current and one of said asymmetrical units, a circuit for the other detector relay including a source of alternating current and the remaining asym- 30 metrical unit, and a circuit for the second winding of said track relay including a source of alternating current and a front contact on each said detector relay.

8. In combination, a first and a second 35 section of railway track separated by insulated joints in the track rails, a source of alternating current connected across the rails of said first section, two impedances one interposed between each rail and said 40 source, a track relay having two windings one of which is connected across the rails of said second section, two asymmetrical units one connected across each said insulated joint, a first detector relay having one 45 terminal connected with one rail of said second section and the other terminal connected directly with one terminal of said source, a second detector relay having one terminal connected with the other rail of the second 50 section and the other terminal connected directly with the remaining terminal of said source, said two detector relays being

responsive to uni-directional current but not to alternating current, and means controlled by said detector relays for supplying alternating current to the remaining winding of 55 said track relay.

9. Means for checking an insulated rail joint comprising an asymmetrical unit connected in parallel with said joint, a relay 60 responsive to uni-directional current but not to alternating current, and a circuit for said relay including said asymmetrical unit and a source of alternating current.

10. Means for checking insulation 65 comprising an asymmetrical unit connected in parallel with said insulation, a relay responsive to uni-directional current but not to alternating current and a circuit for said relay including said asymmetrical unit and 70 a source of alternating current.

11. In combination, two electric circuits separated by insulation, an asymmetrical unit connected in parallel with said insulation, a detector relay responsive to uni-directional current but not to alternating current, 75 a circuit for said relay including said asymmetrical unit and a source of alternating current, and a second relay controlled jointly by one of the first mentioned circuits 80 and by said detector relay.

12. In combination, two conductors separated by an insulated joint, a first relay having two windings, an electric circuit including one winding of said first relay and one 85 of said conductors, an asymmetrical unit connected in parallel with said joint, a detector relay responsive to uni-directional current but not to alternating current, a circuit, for said detector relay including said 90 asymmetrical unit and a source of alternating current, and a circuit for the remaining winding of said first relay controlled by said detector relay.

13. In combination, two adjacent sections 95 of railway track separated by an insulated rail joint, an asymmetrical unit connected in parallel with said joint, a relay, a circuit for said relay including said asymmetrical unit and a source of alternating current, and 100 governing means controlled in part by said relay.

In testimony whereof I affix my signature.
HOWARD A. THOMPSON.
